UNITED STATES PATENT OFFICE

CHARLES A. JACKSON, OF RIDGEWOOD, NEW JERSEY

ELECTRICAL APPARATUS

Application filed May 28, 1927. Serial No. 195,028.

This invention relates generally to electrical power generating equipment and more particularly to improvements in both the electric generator and the driving means therefor.

The power unit specifically considered in this application, which is a continuation in part of my co-pending applications, Serial No. 135,756, filed September 16, 1926, and Serial No. 152,136, filed December 2, 1926, is not only particularly adapted for automatically supplying current in theatres, hospitals and the like, in case of an emergency, such as when the main city current fails, but due to an improved combination of elements in the generator the latter is rendered available for purposes where a relatively constant voltage is desired under varying operating conditions.

One object of my invention is to provide an improved generator adapted to maintain a substantially constant voltage during speed fluctuations. A more specific object in this respect is to provide an improved combination of elements including the generator field and means for automatically controlling the current therein, thereby to effect substantially constant voltage. A further object is to have an automatic thermal control operated by the generator current and so arranged in the improved combination as to maintain voltage regulation during speed fluctuations.

Other objects are; to provide an improved arrangement of controlling element for the generated current and the generator driving mechanism which is specifically shown in this application to be a hydraulic turbine, although it will of course be understood that other driving means may be used such as steam turbines or the like; to provide an improved arrangement whereby a valve for controlling turbine actuating fluid may be adjusted through a wide range without affecting operation of a switch which controls the

generator current; to provide an improved combination of elements including a quick-throw switch and operating means therefor and to provide an improved arrangement for conducting fluid flow to and from the hydraulic turbine.

Other objects and advantages will be seen from the following description of the accompanying drawings, in which:

Fig. 1 is a vertical sectional view through the prime mover and controlling means therefor.

Fig. 2 is a side elevation of the prime mover and generator.

Fig. 3 is a generator wiring diagram including my thermal control.

Fig. 4 is a partial sectional elevation of the adjustable resistance shown in the diagram of Fig. 5.

Fig. 5 is a wiring diagram of a further modified arrangement including the automatically adjustable resistance element.

Figs. 6 and 6a are graphs showing respectively without and with variable field control the relation between the generator voltage R. P. M., and the load.

Fig. 7 is a graph showing the relation between the current and resistance of the thermal control, and

Fig. 8 is a diagram of the emergency and main supply circuits and showing diagrammatically the switch and relation of other parts.

In small electrical generator units, where it is necessary to maintain a relatively constant voltage during speed and load fluctuations, it is desirable to provide a voltage regulating arrangement which is not only efficient but is also simple and inexpensive in construction, maintenance and operation. Due to the relatively low cost of a small unit, elaborate and expensive speed controlling or governing devices are not warranted as in large units. My arrangement, however, by doing entirely away with speed governing

mechanism, is particularly adapted for small units, whether the generator be driven by a hydraulic or steam turbine. However, in any type of small fluid operated unit, and possibly other types, due to the small capacity thereof and its relative sensitiveness to speed fluctuations caused either by load variations or fluctuations in power supply, it is most desirable to have an efficient control. Various arrangements have heretofore been proposed in an attempt to meet certain of the above conditions. Such prior devices have included, for instance, magnetic drags or dampers to prevent overspeeding of the generator, resistance chokes in the main circuit and the use of a field for "bucking" the normal generator field when normal conditions exist. While these arrangements may accomplish results to a certain extent, the results are not obtained as efficiently, simply or effectively as in my arrangement.

In my direct current generator G as shown in Fig. 3, I employ a shunt field S_h and a series field S_e . By making the series field constitute the major field strength, possibly 75% of the total, and by using the type of generator I have shown in combination with an uncontrolled hydraulic turbine, it is possible to effect a substantially constant voltage during load and speed fluctuations. This result is possible, as is shown in my co-pending applications, due to the turbine speed being practically inversely proportional to its load. Hence there is a peculiar combination of operating characteristics between a hydraulic turbine and a generator of the type herein disclosed.

In order to obtain closer voltage regulation in the arrangement just described, and to obtain such regulation with an extremely simple and efficient means, I propose the further use of a thermal regulating member R_e which I place across the series field S_e . This thermal control which is self-contained both as to operation and construction consists preferably of a series of wires Y, made of iron or those alloys having characteristics similar to iron, one example being nickel steel. These wires are connected in parallel and constitute a unit connected by wires A and B across the series field thereby to control bypassing of current around the series field. Instead of several wires Y, a single wire could be used of suitable size and in any case the wires would be suitably enclosed in a container adapted to exclude air from the wires. A characteristic of these control wires, which lends itself particularly for cooperation with my field arrangement, is that with an increase of current through the wires the latter become heated and the resistance thereof automatically increases. This relation exists through such a relatively wide current range that when the load increases and the speed of the generator decreases, the resistance of

the wires automatically increases, thereby forcing more current to pass through the series field. This results in increased voltage, even though the generator speed may have fallen. Conversely, when the load drops the thermal control wires or resistance R_e will cool and in doing so their resistance drops thereby permitting a greater amount of current to be by-passed around the series field through wires A-B, resulting in a reduced field current. This reduced field current, however, does not lower the generator voltage, because as the load decreases the generator speed increases and maintains the voltage constant with the smaller field current.

If it is desired to obtain even closer voltage regulation than that just described, a thermal control R_h may be placed in series with the shunt field. In operation, as the load is decreased the generator speed increases with the result that the voltage impressed across the shunt field is increased. An increase of voltage would cause a greater amount of current to flow through the thermal control R_h resulting in the wires thereof becoming heated and offering more resistance thereby holding back current flow through the shunt field. This reduces the field strength of the shunt field and thus tends to effect reduction of the generator voltage. Therefore, an increase of generator speed will not produce a proportionate increase of voltage by the shunt field, as would be the case without the thermal control R_h , the resistance of which automatically rises and falls in accordance with the impressed voltage or, in equivalent terms, with the speed of the generator.

Conversely, when the load increases and the generator speed decreases, the impressed voltage across the shunt field S_h decreases, resulting in the thermal control R_h lowering in temperature and likewise resistance, thereby permitting more current to flow through the shunt field. Increase of the shunt field current tends to proportionately increase the generator voltage, thus helping to maintain the same constant, even though the generator speed drops. Thus, when the two resistance elements R_e and R_h are employed voltage regulation is made doubly effective.

From the foregoing it is seen that irrespective of the use of control R_h the combination of the series field S_e and control R_e are operative in accordance with variations in speed and load to maintain a relatively constant voltage. Also irrespective of the use of control R_e the combination of the shunt field S_h and control R_h are operative in accordance with variations in speed, thereby to maintain substantially constant voltage. These two combinations may be used alone or together. The combination of the series field and its control alone is more particularly adapted for the specific purposes disclosed in this application, while the combination of the

shunt field and its control alone is more particularly adapted for variable speed units such as locomotive head light generator units wherein a variable power supply of actuating fluid must be contended with. In most instances, if not all, both the series and shunt fields will be used together, although the use or non-use of their respective thermal control will depend upon the field of service just 10 explained.

If it is desired to have the automatic controls R_e and R_h of relatively small capacity, supplemental manually adjustable rheostats r may be inserted in series with the respective 15 controls. These rheostats can be adjusted for a rough approximation of the voltage desired, thereby leaving the automatic controls to take care of the finer adjustments to obtain the necessary substantially constant voltage. In 20 case of the thermal control R_h the wires thereof will be so proportioned that during normal operation it will offer an amount of resistance (or voltage drop across the control) intermediate its high and low points on the 25 curve shown in Fig. 7, thereby permitting a wide range of control either above or below normal voltage.

A wiring diagram and switch arrangement preferably used is diagrammatically shown 30 in Fig. 8, wherein city current is supplied through main supply lines 45 and 46 across which is disposed the automatic starting solenoid 40. The wire 45 is connected to the stationary switch element 47, this in turn being 35 adapted for connection to the other switch element 48 by switch arms 49. Switch element 48 is in turn connected by a wire 50 to a stationary element 51 of a second switch, element 51 in turn being connected to the main 40 line 46 as by wires 52, 53 and 54. The exit lights 55, in case such lights are used as in theatres, etc., will be connected across wires 53 and 54, as will also emergency lights 56. The second switch has arms 57 adapted to 45 connect element 51 with a similar element 58, it being noted that the arms 57 and 49 are angularly disposed and diagrammatically shown as pivotally mounted upon separate shafts which are insulated as at 59.

50 A wire 60 leads from one side of the generator to switch element 58, while the wire 54 continues on around to the other side of the generator. In order to permit operation of the emergency lights independently of the switch 30, there is provided a wire 61 and switch 62.

The quick-throw feature of the switch 30 may be accomplished with any standard type of quick-throw mechanism, but as the specific feature of such a device does not per se constitute a part of my invention, the details thereof have not been shown.

55 The driving means, which is herein shown as a hydraulic impulse turbine but which could be of the reaction type such as shown in

my co-pending application or could be a steam turbine, comprises a suitable structure 1 for housing and supporting a standard type of impulse wheel 2, which is mounted upon a shaft 3 preferably directly connected to the 70 generator G. Actuating fluid, as is usual, is supplied through an inlet pipe 5 and nozzle 6, which is controlled by a suitable needle 7. In some installations it is desirable to permit discharge water to be conducted away 75 either in the direction of the inlet or opposite thereto, and to accomplish this the outlet 8 is made reversible merely by removing bolts 9, turning the outlet and then reinserting the bolts.

The control for the unit here shown is particularly adapted for emergency purposes, such as in hospitals, theatres and the like, this phase of the operation being more fully described in my application Serial No. 152- 80 136, filed December 2, 1926, although the present application has certain improvements thereover which will be understood from the following description. The needle 7 is normally held in closed position and adapted to be opened automatically when the main city supply current fails, the opening of the needle valve thereby automatically starting the unit and generating an emergency supply of current. The controlling elements 85 consist briefly of a stem 7' extending rearwardly through a suitably packed gland and being pivotally connected as at 9 to an operating lever 10, the lower end of which is pivotally connected to a link 11, in turn pivotally connected to a normally stationary but adjustable element 12. A compression spring 13 is interposed between a packing gland 14 and an adjustable nut 15, which is threaded 90 connected to the rod 7', thereby always maintaining a constant force on the rod 7' in a direction for opening the needle valve. To hold the needle valve in closed position a latch bar 16 is pivotally connected as at 17 to the lever 10, while its other end is constantly urged upwardly by a flat spring 18, which is secured to the stationary casing 19. A pin and slot arrangement 20 guides the 95 free end of the latch bar 16 and said bar is adapted to move vertically through an opening 21 in the casing 19, thereby to permit engagement or disengagement of co-operating latch members 22 and 23. These members are made removable to permit replacement in 100 case of wear. Outward movement of latch bar 16 and needle 7 is controlled by an abutment 24 which is carried on suitable studs 25 projecting outwardly from the casing 19 on each side of the latch bar. A collar 26 is secured to the latch bar and when in its outer position abuts member 24. Adjustment of member 24 is affected by nuts 27 disposed on 105 each side of abutment 24 and threaded on the studs 25.

110 The driving means, which is herein shown as a hydraulic impulse turbine but which could be of the reaction type such as shown in 115

To permit the emergency generator current 120

and the city current to be distributed over the same wires in the hospital, theatre or the like, the switch mechanism 30 is provided, whereby when the emergency generator current is available the same is connected to the distributing wires and the city circuit is disconnected and vice versa. To accomplish this in an efficient manner, and to permit adjustment of the needle valve 7, I have provided 10 the following arrangement in distinction to the one described in my co-pending application, Serial No. 152,136. Herein, the switch 30 is of the quick-throw type, having a pivoted, forked operating arm 31. The 15 inner surface of each fork is adapted for engagement by a pin 32, which is carried upon a rod 33 slidably mounted in a suitable bearing 34, this bearing having a slot 35 to receive the pin. The length of the bearing 20 slot permits considerable outward movement of the rod and pin 32, as shown by dotted lines in Fig. 1.

By this arrangement, it is possible to effect 25 considerable adjustment of the needle valve through the nuts 27 without in any way affecting either the extent or quickness of operation of the switch.

To release latch bar 16 a solenoid 40 is connected in series with the city circuit and the 30 solenoid core carries a hammer 41 adapted to fall and strike the latch bar 16 when the city circuit fails, thereby depressing spring 18 and the latch bar to disengage latch members 22, 23. Spring 13 then forces needle valve 7 35 open and the water wheel starts up and current is generated, the city supply means being simultaneously disconnected from, while the generator current is connected to, the distributing wires.

40 In the modified arrangement of controlling the series field in accordance with the generator load, there is provided as shown in Fig. 4 a solenoid 50. This device comprises current and voltage coils 66 and 67 respectively, 45 within which is disposed a suitable solenoid core 68. An oil dashpot 69 has a ported piston 70 connected to the lower end of the core while the upper end thereof is connected to a lever 71 normally pulled downwardly by an 50 adjustable tension spring 72. The other end of lever 71 is pivotally supported upon a bracket 72', which carries any suitable variable resistance, herein disclosed preferably as a carbon pack 73, the terminals of which are, 55 74 and 75, while variable resistance is obtained by varying pressure upon a plunger 76 through an adjustable set screw 77 carried by the lever 71.

59 In Fig. 5 this supplementary field control 59 is diagrammatically shown in the wiring diagram. As shown the generator G has a usual shunt field 80 adapted if desired to be controlled by a manually operated rheostat 81, while a series field 82 is disposed as usual in one of the main lines 83. The other main line

84 passes by way of line 85 to the current coil 66 of the solenoid 50 and out through a continuation of the main line 84. The voltage coil 67 is connected across lines 83 and 84 by wires 87 and 88, while the field resistance carbon pack 73 is connected across the terminals of the series field 82 by wires 89 and 90. Assuming that the desired shunt field regulation is obtained for any given seasonal load, when the turbine speed increases or drops the current and voltage coils 66 and 67 will operate through solenoid core 68, lever 71 and plunger 76 to vary the resistance 73 and variably control the current flow through the series field 82, thereby to maintain a voltage regulation which is very close and fully comparable to that voltage regulation obtained by the speed governed turbine units.

The degree of voltage regulation obtained by any of my improved combinations is diagrammatically shown in Fig. 6 and Fig. 6a. As shown in Fig. 6a for wide turbine speed variations the voltage is a substantially straight line. While the line is shown as slightly increasing as the load increases, which is desirable, it may by properly proportioning either the resistance 81 or the shunt series field coils be made to take any desired inclination. In the form of control shown in Fig. 4, the dashpot 69 insures smooth operation of the resistance 73, thereby preventing any sudden changes of the series field. The degree of greatest resistance of the carbon pack 73 may be adjusted by a set screw 92.

I claim:

1. The combination in a power generating apparatus including a prime mover having means which is invariable during operation for conducting flow of power medium thereto, a generator driven by said prime mover, means for creating a total effective field flux including a field circuit adapted upon variations of current therein to vary, in the same direction, the total effective field flux, and thermal means arranged with respect to said field circuit so as to control current therethrough automatically in accordance with the generator load which is coordinated in a predetermined manner with turbine speed which increases with decreased load and vice versa.

2. The combination in a power generating apparatus including a prime mover having means which is invariable during operation for conducting flow of power medium thereto, a generator driven by said prime mover, a field circuit for said rotor and thermal means variably heated by the generator current and so arranged with respect to said field circuit as to vary current therethrough automatically in accordance with and in a direction opposite to the variations in the generator speed which decreases over a relatively wide range during increasing load and vice versa.

3. The combination in a power generating apparatus including a prime mover having

means which is invariable during operation for conducting flow of power medium thereto, a generator driven by said prime mover, a field circuit, a self-contained thermal operated resistance, means connected thereto whereby the field current is varied automatically in accordance with and in a direction opposite to the variations in the generator speed.

4. The combination in a power generating apparatus including a prime mover having means which is invariable during operation for conducting flow of power medium thereto, a generator driven by said prime mover, a series field circuit, and means including controlling means connected in a circuit parallel with said series circuit whereby during an increase of load current and decrease of generator speed the current through said field and parallel circuits are automatically relatively adjusted and a field strength created to maintain a substantially constant voltage.

5. The combination in a power generating apparatus including a prime mover having means which is invariable during operation for conducting flow of power medium thereto, a generator driven by said prime mover, a series field circuit, and means, including controlling means connected in a circuit parallel with said series field, whereby during increase of load current and decrease of generator speed the current through said field and parallel circuits are automatically relatively adjusted and a field strength created sufficient to maintain a substantially constant voltage, said controlling means being adapted upon a decreased load and increased generator speed to by-pass automatically a greater amount of current around the series field thereby to maintain a substantially constant voltage.

6. The combination in a power generating apparatus, comprising a hydraulic turbine having a substantially fixed flow area during load and speed variations, a generator driven thereby having a series field, and means disposed in parallel with said series field for controlling the current therethrough automatically in accordance with load and speed fluctuations thereby to maintain a substantially constant voltage, said means comprising an electrically heated element the temperature and resistance of which varies in accordance with the current passed therethrough.

7. The combination in a power generating apparatus comprising a hydraulic turbine having a substantially fixed flow area during load and speed variations, a generator driven thereby having a shunt field, and means associated with said shunt field for controlling the current therethrough automatically in accordance with speed fluctuations, thereby tending to maintain a substantially constant voltage.

8. The combination in a power generating apparatus comprising a hydraulic turbine

having a substantially fixed flow area during load and speed variations, a generator driven thereby having a shunt field, and means associated with said shunt field for controlling the current therethrough automatically in accordance with speed fluctuations, thereby tending to maintain a substantially constant voltage, said controlling means comprising an electrically-heated element adapted to have its resistance vary in accordance with the current passed therethrough.

9. The combination in a power generating apparatus comprising a hydraulic turbine having a substantially fixed flow area during load and speed variations, a generator driven thereby having shunt and series fields, means for controlling the current to said fields automatically in accordance with load and speed fluctuations, thereby tending to maintain a substantially constant voltage.

10. The combination in a power generating apparatus comprising a hydraulic turbine having a substantially fixed flow area during load and speed variations, a generator driven thereby having shunt and series fields, means for controlling the current to said fields automatically in accordance with load and speed fluctuations, thereby tending to maintain a substantially constant voltage, said controlling means comprising an element the resistance of which automatically varies in accordance with the current passed therethrough.

11. The combination in a power generating apparatus comprising a hydraulic turbine having a substantially fixed flow area during load and speed variations, a generator driven thereby having shunt and series fields, means for controlling the current to said fields automatically in accordance with load and speed fluctuations, thereby tending to maintain a substantially constant voltage, said means comprising elements the resistance of which varies automatically in accordance with the current passed therethrough.

12. The combination in a power generating apparatus comprising a hydraulic turbine having a substantially fixed flow area during load and speed variations, a generator driven thereby having shunt and series fields, the latter of which produces approximately 75% of the effective field flux, and means disposed in parallel with said series field for controlling the current therethrough automatically in accordance with load and speed fluctuations thereby to maintain a substantially constant voltage, said means comprising an electrically heated element the temperature and resistance of which varies in accordance with the current passed therethrough.

13. The combination in a power generating apparatus including a prime mover having means which is invariable during operation for conducting flow of power medium there-

to, a generator driven by said prime mover, shunt and series fields arranged for accumulative action and means including a thermal resistance unit, variably heated by the current passing therethrough, for varying the total field flux automatically in accordance with variations in the supply of current to said thermal means.
